UNITED STATES PATENT OFFICE.

WADE H. WINEMAN, OF MICHIGAN CITY, INDIANA, ASSIGNOR TO SULLIVAN MACHINERY COMPANY, A CORPORATION OF MASSACHUSETTS.

GAUGING DEVICE.

Application filed July 13, 1920, Serial No. 395,950. Renewed May 27, 1924.

To all whom it may concern:

Be it known that I, WADE H. WINEMAN, a citizen of the United States, residing at Michigan City, in the county of Laporte and State of Indiana, have invented certain new and useful Improvements in Gauging Devices, of which the following is a full, clear, and exact specification.

My invention relates to gauging devices, and more particularly to gauging devices for imparting a proper gauge and taper to the forward end of a drill bit or similar tool.

An object of my invention is to provide an improved gauging device for tool sharpening mechanisms. A further object of my invention is to provide an improved gauging device which will provide accurate step by step adjustment of the dies and permit locking of the same in each position. A still further object of my invention is to provide, for use with gauging dies, an improved adjusting means for one of said dies comprising a member serving either as a handle for adjustment or as a lock for said parts. Other objects of my invention will appear during the course of the following specification.

In the accompanying drawings I have shown, for purposes of illustration, one embodiment which my invention may assume in practice.

In these drawings,—

Fig. 1 is a side elevation of a portion of the clamping mechanism of a drill sharpener provided with the illustrative form of my improved gauging device.

Fig. 2 is a front elevation with parts broken away to show the construction in greater detail.

Fig. 3 is a plan view of my improved gauging mechanism.

Fig. 4 is a section on the line 4—4 of Fig. 2 showing a detail of construction.

Fig. 5 is a plan view of the lower die.

In drilling rock it is a well known fact that during the progress of drilling a hole, the bore of the hole progressively decreases in size, this being due to the fact that the lateral edges of a drill bit and the side surface of the forward end thereof wear away comparatively rapidly due to their friction on the rock, and accordingly, at the frequent changes of steels which are necessary, it is requisite that a steel having a bit of slightly smaller gauge than that last used be substi-

tuted for the drill which it is replacing. It is of course desirable, particularly in drilling a deep hole, to make the changes of gauge as small as possible, for the amount of material that has to be drilled out increases very rapidly as the diameter of the hole increases. I have found in practice that it is highly desirable to form drill bits with a double taper so formed as to provide reaming edges, i. e., with an initial taper from the shank of say 12 or 14 degrees and a final taper adjacent the cutting edges of 5 or 7 degrees and with the peripheral surface of the forward end of the bit so formed as to bring the edges of the wings into a cylindrical surface. There is thereby provided a bit having high wear resisting properties and, owing to the formation of the peripheral wing surface adjacent the cutting edges, one which reduces to a minimum the changes in gauge at the time of changing steels. I have also found that reaming edges formed on a drill bit of the well known double arc double taper type produce a bit of very high efficiency. For the purpose of providing a very simple, rugged and readily operated means for effecting accurate gauging, the formation of a double taper and of a reaming edge, I have devised the mechanism which comprises the subject matter of the present application.

In the illustrative embodiment herein disclosed, the lower jaw of a vise mechanism which is adapted to clamp a drill steel for the purpose of holding it during dollying operation is indicated at 1. The upper jaw of the vise is indicated at 2 and lodged in the two jaws are a pair of dies 3 and 4 for the purpose of holding the drill during the operation mentioned. In the present device I secure to the lower jaw 1 a stationary lower die member 10 provided with a pin 11 seated in a socket 12 formed in the lower jaw, said pin constituting die holding means. The rear face 13 of the lower die block seats against the forward face 14 of the lower vise jaw and in cooperation with the pin 11 and socket 12 furnishes a rigid mounting for the lower die block. As is well known, the jaw 2 of the vise is readily reciprocable under suitable manual control and I have secured to this upper jaw a movable die 15 to cooperate with the stationary die 10. Rigidly bolted to the front face of the upper vise jaw and having a tenon 16 adapted to fit a

mortise 17 formed in the front face of the jaw is a die carrying block 20 which is provided with an upwardly directed tubular portion 21 and with a lower reduced bore 22 communicating with a somewhat enlarged bore 23 in the section 21. The upper die 15 is longitudinally slidable in the bore 22 but is prevented from rotation by means of a groove or opening 24 and a fixed retaining pin 24' which is horizontally arranged in a bore 25 intersecting the bore 22 radially. The pin 24' is maintained in its inmost position with respect to the groove 24 by means of a washer 26 mounted on a machine screw 27 secured in the block 20 and having a spring 28 between a second washer 26 adjacent the head of the screw 27 and the first mentioned washer 26 to press the latter, and accordingly the pin 24, inwardly. For the purpose of adjusting the die 15 I have threaded the interior of the upper end of the member 21 as indicated at 30 and have mounted a large square-headed follower screw 31 therein, the threads of the screw 31 being relatively coarse to permit endurance of the shock of the blows imparted by the upper jaw 2. Cooperating with the squared head 32 of the follower screw 31 is a combined handle and locking member 33 having a socket 34 therein fitting the squared head 32 and a lug 35 projecting laterally and provided with a pin 36 at right angles thereto. The upper end of the member 21 is provided with an annular flange 37 and in the flange are formed two notches 38 and 39 separated by an angle of 135 degrees, these notches being adapted to receive the handle pin 36 and hold the follower screw 31 against turning.

I have found in practice that a gauge variation of one-thirtieth of an inch or multiple thereof will be sufficient for most purposes and accordingly I have provided a screw connection between the follower screw and the top of the member 21 of four threads per inch. Noting the position of the handle 36 in Figs. 2 and 3, and assuming that it be desired to decrease the gauge by one-thirtieth of an inch, the procedure will be as follows: The member 33 will be lifted vertically off the top of the squared member 32 of the follower screw 31. It will then be turned over about a horizontal axis in such manner that the handle 36 pro-

jects in the opposite direction and about a vertical axis in such manner that the handle 36 is diametrically opposite its original position with respect to the follower screw 31. The member 33 will then be again fitted to the projecting stub 32 and turned through an angle of 45 degrees clockwise in Fig. 3. The member 33 will then be removed and inverted about a horizontal axis and the pin 36 inserted in the groove 39 and member 33 fitted to the squared stub 32. The result of this manipulation will be the turning of the follower screw 31 through an angle of 45 degrees or one-eighth of one revolution and accordingly the upper die 15 will be lowered one-eighth multiplied by one-fourth or one-thirtieth of an inch.

From the foregoing description the mode of adjustment of the dies will be readily apparent, it being obvious that to effect increase in gauge the direction of rotation of the follower screw will be reversed and that the first blow upon the steel will cause the die 15 to slip upwardly to its proper position where it will be held by the friction between the pin 24' and the groove 24. It will be noted that the lower die block 10 is provided with a depression in its upper surface which is tapered angularly at its forward end and deeper at its forward end than adjacent the rear, this surface being adapted to receive and impart to one wing of a drill bit the proper taper, contour and gauge. The upper die 15 is provided with a gauging surface 42 which is formed with a suitable mean radius for the average drill bit which will be formed therein and the upper gauging surface 42 and the lower gauging surface 41 have the same relative angle to a horizontal line and accordingly will gauge a bit inserted between them accurately while at the same time imparting a change of taper to the forward end as may be necessary. If it were desired to use a coarse thread on the screw 31 and to decrease the gauge changes, it would obviously be possible to increase the number of sides on the member 34 while still retaining it of regular polygonal shape, and then place the notches 38 and 39 apart an odd multiple of one-half the angle subtended by each side of the polygon. The minimum change in gauge would be then equal to

$$\frac{1}{\text{threads per inch}} \times \frac{360}{\text{angle subtended by each side of polygon}}$$

2

From the foregoing description it will be obvious that I have provided an improved, simple and efficient gauging mechanism comprising fixed and movable dies, which is readily adjustable and positively locked in position when adjusted.

While I have in this application specifi-

cally described one form which my invention may assume in practice, it will be understood that this form of the same is shown for purposes of illustration and that the invention may be modified and embodied in other forms without departing from its spirit or the scope of the appended claims.

What I claim as new and desire to secure by Letters Patent is:

1. In a drill sharpening machine, a stationary jaw, a movable jaw, said jaws constituting the jaws of a vise, and gauging means secured to said jaws comprising a fixed die member secured to said stationary jaw and an adjustable die member secured to said movable jaw. 65
2. In a drill sharpening machine, stationary and movable vise jaws, gauging means including a die carried by each of said jaws, and means movable in a path parallel to the path of movement of said movable jaw for adjusting the operative relation between said dies. 70
3. In a drill sharpening machine, stationary and movable vise jaws, a gauging die carried by each of said jaws, and means movable about an axis parallel to the path of movement of said movable jaw for adjusting the operative relation between the dies. 75
4. A gauging die mechanism comprising stationary and movable die members, actuating means therefor, and means positively actuated by said actuating means and movable relative thereto for moving relatively the working faces of said dies in an angular direction. 80
5. A gauging die mechanism comprising stationary and movable gauging dies, means providing a relatively rigid support for each of the same, and rotatable means movable relative to one of said dies for adjusting the working faces thereof away from or towards each other. 85
6. A gauging die mechanism comprising stationary and movable gauging dies, means providing a supporting base for each of said dies and which are unyielding relative thereto during actual gauging of the work piece, and screw operated adjusting means cooperating therewith to cause the working faces of said dies to move toward or away from each other. 90
7. A gauging die mechanism comprising stationary and movable dies, means for adjusting the gauging effect of said dies including a bracket and a rotatable screw cooperating therewith, and means providing a supporting base for said dies which are rigid relative thereto during the final stroke of the gauging operation. 95
8. A gauging die mechanism comprising stationary and movable dies, means for effecting an exact gauge of a work piece, and means for adjusting the gauging effect of said dies including a bracket, and a rotatable member supported thereby. 100
9. A gauging die mechanism comprising stationary and movable dies, means for effecting an exact gauge of a work piece, means for adjusting the gauging effect of said dies including a bracket, means forming a nut, and actuating means cooperating therewith, one of said means being rotatably supported by said bracket. 105
10. In a drill sharpening machine, a stationary jaw, a movable jaw, said jaws constituting the jaws of a vise, and gauging means secured to said jaws comprising a fixed die member secured to said stationary jaw and an adjustable die member having a housing in which it is longitudinally adjustable secured to said movable jaw. 110
11. A gauging die mechanism comprising stationary and movable die members, means for effecting an exact gauge of a work piece irrespective of substantial variations in the work piece, said movable die member being provided with an adjusting screw coaxial therewith but separate therefrom and adapted to directly engage the same. 115
12. A gauging die mechanism comprising stationary and movable die members, said movable die member being provided with an adjusting screw coaxial therewith but separate therefrom, and having a longitudinal groove therein and means cooperating with said groove to prevent rotation of said die member. 120
13. A gauging die mechanism comprising stationary and movable die members, said movable die member being provided with an adjusting screw coaxial therewith but separate therefrom, and having a longitudinal groove therein and elastically held means cooperating with said groove to prevent rotation of said die member. 125
14. A die mechanism comprising a stationary die member, a movable die member, adjusting means for the latter comprising a screw coaxial with said movable die member, means for preventing angular movement of said die member, and combined adjusting and locking means for said screw. 130
15. A die mechanism comprising a stationary die member, a movable die member, adjusting means for the latter comprising a screw coaxial with said movable die member, means for preventing angular movement of said die member, and combined adjusting and locking means for said screw operable in reverse positions as an adjusting handle or as a locking means. 135
16. A die mechanism comprising a stationary die member, a movable die member, adjusting means for the latter comprising a screw coaxial with said movable die member, means for preventing angular movement of said die member, and adjustable means for varying the position of the movable die comprising a screw in alignment with said die, a polygonal shank upon said screw, a member having a polygonal opening to fit said shank, a member secured to said last mentioned member and making an angle with the plane of said preceding member, 140

and means cooperating with said last mentioned member in one position thereof to lock said screw.

17. A die mechanism comprising a stationary die member, a movable die member, adjusting means for the latter comprising a screw coaxial with said movable die member, means for preventing angular movement of said die member, and adjustable means for varying the position of the movable die comprising a screw in alinement with said die, a polygonal shank upon said screw, a member having a polygonal opening to fit said shank, a member secured to said last mentioned member and making an angle with the plane of said preceding member, and means cooperating with said last mentioned member in one position thereof to lock said member, the member fitting said polygonal shank being reversible and when reversed from the position mentioned, constituting adjusting means for said screw.

18. In combination, an adjustable die member, adjusting means therefor comprising a coaxially arranged screw, mechanism providing for the locking of said screw in a fixed position comprising a polygonal head on said screw, a member having a socket fitting the polygonal head, a member projecting downwardly from said last mentioned member, and a fixed member cooperating with said last mentioned member and having slots therein for the reception of said last mentioned member, said slots being separated by an odd multiple of one half the angle subtended by each side of the polygon.

19. In a drill sharpening machine, a stationary member, a movable member, and gauging means secured to said members comprising a fixed die member secured to said stationary member and constituting both a forming die and an abutment and an adjustable die member secured to said movable member and adjustable with respect thereto to vary the distance between a given point therein and an opposite point in the other die member.

20. In a drill sharpening machine, a stationary member, a movable member, and gauging means secured to said members comprising a fixed die member secured to said stationary member and constituting both a forming die and an abutment and an adjustable die member secured to said movable member and adjustable with respect thereto in a path parallel to the direction of movement of said movable member to vary the distance between a given point in said movable die and an opposite point in the other die member.

21. A gauging die mechanism comprising stationary and movable die members, said movable die member being provided with adjusting means operative to change the

position of the die in a direction parallel to its direction of operative movement and said stationary die member constituting both forming and abutment means.

22. A gauging die mechanism comprising stationary and movable die members, means for effecting an exact gauge of a work piece irrespective of substantial variations in the work piece, said movable die member being provided with a separate adjusting screw arranged with its axis parallel to a line parallel to the axis of adjustment of the die, said screw directly abutting said die.

23. In a drill sharpening mechanism, relatively reciprocable die carrying members, relatively reciprocable cooperating die members fixed during operation relative to said relatively reciprocable die carrying members, and screw means for changing the position of one of said die members relative to its carrying member at will comprising a screw separate from and directly engaging said last mentioned die member.

24. A gauging die mechanism comprising stationary and movable die members, said stationary die member constituting both forming means and an abutment member for positioning the work piece and comprising a substantially square base portion fixed as to movement laterally.

25. A gauging die mechanism comprising relatively reciprocable die members, one of said members constituting both forming means and an abutment member for positioning the work piece and comprising a substantially square base portion, a support for said base, and means cooperating with said support for holding said base fixed as to movement laterally, said base having means presenting a surface adapted by contacting action with the surface of said support to limit during an actual gauging operation longitudinal movement of said base in one direction.

26. In a drill sharpening mechanism, a stationary die member comprising a block having angularly disposed portions one of which is horizontal and of small length in a direction parallel to the axis of a work piece, a tapering recess in said last mentioned portion, and an abutment means formed by said other portion arranged at the deeper end of said recess.

27. In a drill sharpening mechanism, a stationary die providing a recess of increasing depth from one end thereof and an abutment having angularly disposed walls lying in substantially vertical planes, said die having a horizontal base and a vertical part each adapted to engage a supporting surface and comprising also a central pin projecting from its base.

28. In a drill sharpening mechanism, a base having angularly disposed surfaces, and a gauging die having surfaces cooperating

with said other surfaces and normally having a single operative position and adapted to be vertically removed.

29. In a drill sharpening mechanism, a die supporting base having angularly disposed surfaces, a gauging die having surfaces contacting with said angular surfaces to retain said die in only a single operative position during an actual gauging operation, certain of said contacting surfaces preventing longitudinal movement of said die in one direction, and vertically movable die holding means.

30. In a drill sharpening mechanism, a base having a horizontal supporting surface and a plurality of surfaces projecting away from the plane of said horizontal surface, and a die normally having a single operative position and having surfaces cooperating with said other surfaces, certain of said surfaces providing an end abutment for said die.

31. In a drill sharpening mechanism, a base having a horizontal supporting surface and a plurality of surfaces projecting away from the plane of said horizontal surface, and a die normally having a single operative position and having surfaces cooperating with said other surfaces, certain of said surfaces providing an end abutment for said die and adapted to prevent lateral movement thereof.

32. A gauging die mechanism comprising a base having a plurality of relatively angularly disposed surfaces, and a die having surfaces cooperating with said other surfaces, certain of said surfaces forming an end abutment for said die and adapted to cooperate to prevent lateral movement of the end of said die which has the abutting portion.

33. In a drill sharpening mechanism, a base and a member movable relative thereto each of which carries a cooperating die for operating upon a work piece, gauging mechanism including a die for also operating upon said work piece, and means for adjusting said gauging die movable in a path parallel to the path of movement of said movable member, said cooperating and gauging dies and adjusting means being disposed substantially adjacent each other.

34. A gauging die mechanism comprising relatively movable gauging dies, one of which has a cylindrical portion with a radial opening, and a radially extending retaining member cooperating with said opening. 55

35. A gauging die mechanism comprising relatively movable gauging dies, one of which has a radial opening, and a radially yieldable retaining member cooperating with said opening. 60

36. A gauging die mechanism comprising a base having supporting and positioning surfaces, a gauging die held by gravity on said supporting surface, said die having surfaces contacting with said positioning surfaces, and means whereby said die is maintained in an operative position by said surfaces during an actual gauging operation. 65 70

37. A gauging die mechanism comprising a base having supporting and positioning surfaces, and a gauging die held by gravity on said supporting surfaces, said die having surfaces contacting with said positioning surfaces to maintain said die in an operative position during an actual gauging operation, certain of said positioning surfaces being plane and disposed so as to positively prevent longitudinal movement of the die in 80 one direction. 75

38. A gauging die mechanism comprising a base having a horizontal supporting surface and a vertical positioning surface, and a gauging die held by gravity on said horizontal surface and having a surface contacting with said vertical positioning surface to restrain said die from moving to an inoperative position during an actual gauging operation. 85 90

39. A gauging mechanism comprising means presenting a supporting surface and an abutment, a gauging die adapted to have contact with said abutment and said surface, and means for holding the die against movement away from said abutment. 95

40. A gauging mechanism comprising means presenting a supporting surface, a gauging die, and means for holding said die against horizontal movement on said surface, 100 said means being vertically movable to allow removal of said die.

In testimony whereof I affix my signature.
WADE H. WINEMAN.
